UNITED STATES PATENT OFFICE.

RÉGIS DARNE, OF ST. ETIENNE, FRANCE, ASSIGNOR TO ÉTABLISSEMENTS DARNE, OF ST. ETIENNE, FRANCE, A CORPORATION OF FRANCE.

DEVICE FOR REGULATING THE RATE OF FIRE IN AUTOMATIC FIREARMS.

Application filed June 11, 1924. Serial No. 718,443.

To all whom it may concern:

Be it known that I, RÉGIS DARNE, a citizen of the French Republic, residing at St. Etienne, Department of Loire, France, have 5 invented certain new and useful Improvements in Devices for Regulating the Rate of Fire in Automatic Firearms, of which the following is a specification.

The present invention relates to an improvement in automatic fire arms, such as machine guns and automatic rifles, with any operating means such as gas operation or barrel recoil.

The invention consists of a device for allowing the rate of fire to be increased or decreased without altering the admission of gas or the mass of the moving parts.

The accompanying drawings represent by way of example a form of construction 20 for carrying out the invention, in its application to a gas-operated automatic gun.

Figure 1 is a view in axial longitudinal section of the device, with portions in elevation.

Figure 2 is a corresponding partial view 25 showing another position of the moving parts.

Figure 3 is a transverse section upon the line 3—3 of Figure 1.

Figure 4 is a horizontal section upon the line 4—4 of Figure 1.

The movement of the breech bolt m of the gun (i. e. the member carrying the firing pin) is produced in the well known manner 35 in one direction by the admission of a portion of the exploded gases acting upon one end of the bolt (at the left of Figure 1) and in the other direction by the opposing action of the recuperator spring upon the opposite end (to the right of Figure 1); the operating devices mentioned are not shown in the drawings.

Upon this breech bolt m , there is pivoted at m^2 , in a central groove m^1 , a lever n of which the oscillatory movement around its axis m^2 is limited in one direction by a pin m^3 fixed in the groove m^1 and in the other direction by a lug n^1 upon the lever n coming to bear laterally upon the upper flat surface of the breech bolt (Figure 3).

In the breech casing there is rotatably mounted a spindle o upon which is fixed at one side an arm o^1 constituting the regulator for the rate of fire; the spindle o is cut away or shaped in such a manner as to

present a tooth o^2 beneath which there passes a beak n^2 upon the lever n , when the breech bolt m under the action of the thrust of the gases returns in the direction from left to right in Figure 1.

During this movement the lever n dips or rocks as its end n^2 passes beneath the spindle o and then rises immediately under the action of a long flat spring m^4 located at the bottom of the groove m^1 in the breech bolt 65 and exerting pressure at the points m^5 m^6 m^7 .

The position of the spindle o is such that a distance of only five to ten millimetres separates it from the end of the lever n 70 carrying the beak n^2 , when the breech bolt m is at the end of its return stroke that is to say to the right in Figure 1, the recuperator spring being then fully tensioned.

When the breech bolt m comes forward 75 again (towards the left in Figure 1), under the thrust exerted by the recuperator spring, the lever n carried forward by the breech bolt suddenly brings its beak n^2 into contact with the tooth o^2 upon the spindle o of the regulator o^1 ; but at this moment the lever n is no longer able to dip as before but tends on the contrary to lift up higher and higher owing to the relative positions of its pivotal axis m^2 and of its beak n^2 , until arrested 85 by its lugs n^1 making contact with the flat top of the bolt. This lever n is therefore compelled to operate the spindle o of the lever o^1 , causing the latter to perform an angular rotation around the spindle o until 90 when the lever has reached the position represented in Figure 2, its tooth o^2 allows the beak n^2 of the lever n to slip past it.

Upon the arm o^1 there can slide along a guide bar o^4 a knurled disc o^3 carried by a pin o^5 ; the further this disc o^3 is moved away from the spindle o of the regulator arm o^1 , the greater has to be the force exerted upon the beak o^2 by the lever n in order to turn the regulator arm o^1 , thereby reducing the linear speed of the breech bolt m , so as to give a slower rate of fire. The rate of fire of the gun will therefore depend upon the position of the knurled disc o^3 upon the regulator arm o^1 .

If it is desired still further to reduce the rate of firing, there may be arranged upon the gun, one after another, a series of two or more spindles o , each of which comprises an arm o^1 with a regulator disc o^3 , and each 110

of which spindles is situated in such a way that the lever *n* after having slipped past the first spindle *o* comes into engagement with the next, and so on. The mean linear speed of the breech bolt may thus be reduced to an extremely low figure.

The lever *n*, instead of being mounted on the breech bolt *m*, may evidently be carried by any other working part having a rectilinear or curvilinear stroke during the operation of the gun. This movable supporting member may be constituted either by the breech slide or the like of a gas-operated automatic fire-arm for example or by the barrel or by any part moving with the barrel in guns operated by recoil.

What I claim is:

1. A device for regulating the rate of fire in automatic fire arms, comprising a fixed 20 casing, a member having a reciprocating movement in the said casing during the actuation of the fire arm, a spindle rotatably mounted in the said casing, an arm fixed to said spindle so as to rock therewith, 25 a weighted member mounted upon said arm in an adjustable position relatively to the axis of the rocking spindle so as to regulate the inertia of the said arm, a stop member carried by the reciprocating member and 30 adapted to come in engagement with the said spindle and to rock the same and the weighted arm during the movement of the carrier member in one direction, said means allowing of said stop member to slip past 35 the spindle during the movement of the carrier member in the opposite direction, for the purpose described.

2. A device for regulating the rate of fire in automatic fire arms, comprising a breech 40 casing, a breech bolt having a reciprocating movement in said breech casing during the actuation of the fire arm, a spindle rotatably mounted in the said breech casing, an arm fixed to said spindle so as to rock 45 therewith, a weighted member mounted upon said arm in an adjustable position relatively to the axis of the rocking spindle so as to regulate the inertia of the said arm, a stop member carried by the reciprocating

breech bolt and adapted to come in engagement with the said spindle and to rock the same and the weighted arm during the movement of the carrier breech bolt on its firing stroke, said means allowing of said stop member to slip past the spindle during the movement of the carrier breech bolt on its return stroke, for the purpose described.

3. A device for regulating the rate of fire in automatic fire arms, comprising a breech 60 casing, a breech bolt having a reciprocating movement in said breech casing during the actuation of the fire arm, a spindle rotatably mounted in said breech casing, an arm keyed on said spindle so as to rock therewith, a weighted member mounted upon said arm in an adjustable position relatively to the axis of the rocking spindle so as to regulate the inertia of said arm, a tooth provided in said spindle, a groove provided in 70 the breech bolt, a lever pivoted in said groove, a beak at one end of said lever, adapted to come in engagement with the tooth of the spindle and to rock the same during the movement of the breech bolt on 75 its firing stroke, a spring member located in the groove of the breech bolt and adapted to maintain the said lever beak in its engaging position with the spindle tooth during the firing stroke of the breech bolt, and adapted to allow of the lever beak to slip past the said spindle tooth during the return stroke of the breech bolt, and means for limiting the oscillatory movement of the 80 said lever.

4. In a device as claimed in claim 1, the provision, upon the arm fixed to the rotatable spindle, of a guide bar secured to said arm and of a weighted disc adapted to slide upon said guide bar to and from the spindle, for the purpose described.

In testimony whereof I have signed my name to this specification.

RÉGIS DARNE. [L. S.]
